COIN COUNTING DEVICE

Eugen Reis, Bruchsal, Baden, Germany; vested
in the Alien Property CustodianApplication May 31, 1940, Serial No. 338,135
In Germany April 15, 1939

5 Claims. (Cl. 133—8)

This invention relates to a coin counting device of the type in which the coin that is the lowermost at the time being of a pile of coins guided in a vertical tube is ejected by a horizontally movable slide, the coin being utilized for the actuation of means for counting the coins individually for rouleaus of coins, as well as collectively. Concerning counting devices of this type the idea of lifting a vertically guided lever having a roll lying in the path of travel of the individually ejected coins different extents depending upon the thickness of the individual coins is known. As, for instance, the thickness of a 1-pfennig-piece amounts only to 1.1 mm., the stroke of the driving lever is very small, which necessitates the provision of correspondingly large ratios of transmission movement in order to operate the counting device. Considering the unavoidable backlash, or lost motion, in the transmission train the slight driving stroke mentioned is liable to fail to properly operate the counting mechanisms. When such a counting device also is used to count 5-mark-pieces, the thickness of which is more than double the thickness of the 1-pfennig-pieces, it is necessary to compensate for the greater thickness of the coins, by providing for a backlash of more than half the extent of movement imparted to it by the passage of the coin beneath the drive lever. This is effected by the use of helical springs which, owing to their light tension, do not respond sufficiently reliably to the slight "pfennig-stroke," and operate the counting mechanism either not at all or insufficiently.

The present improved coin counting device obviates the above mentioned drawbacks by determining the length of the stroke of the lever mentioned, not according to the thickness of the coins being counted, but according to the diameter of the same, the length of the stroke, as regards, for instance, a pfennig, amounting, therefore, not to 1.1 mm., but to 17 mm., which is transmitted to said lever. The system of piling the coins in a vertical tube and withdrawing them singly from the lower end thereof is maintained, the only requirement being to provide in front of the delivery slot of said tube a member movable parallel to the path of the coins and effective to transmit motion to the counting mechanism.

If said member is a spring-actuated lever which is supported on a rocking shaft located above the above-mentioned slot, the free end of said lever or arm extending into the coin feed path, the further advantage will be obtained that, irrespec-

tive of the different diameters of the coins, the length of movement of said free lever end will be nearly always the same, because the end can be so adjusted that after having traversed a distance of about 15 mm., it escapes past or slides off from the leading edge of the coin and now rests upon the upper surface of the same. The just mentioned action varies slightly according to the different thicknesses of the coins, but the difference between the feed as regards a pfennig-piece and the feed as regards a 5-mark-piece amounts, if the minimum length of the stroke amounts to about 15 mm., only to from 2 to 3 mm. The differences between the lengths of the strokes can, therefore, be rendered extraordinarily uniform.

The driving system designed according to this invention results in the use of only a few levers with normal ratio proportions. The grand total 20 counting mechanism, for instance, can be actuated directly from the rotary shaft of the driving feed lever by means of a simple lever, and in the same manner the counting mechanism for individual rouleaus or amounts of coins can be 25 actuated merely by the intermediary of a longitudinal drive member. The small number of the levers reduces considerably the total play of or lost motion in the device and the acceleration of 30 the masses so that a higher number of revolutions per unit of time is made possible.

The invention is illustrated diagrammatically and by way of example in the accompanying drawings in which Figure 1 is a side-view of the machine, illustrating the arrangement of the new system of levers, Figure 2 is a part-plan view pertaining to Fig. 1, and Figures 3 and 4 show details fully explained hereinafter.

In the drawings, 1 (Fig. 1) denotes the counting table upon which the coins are dumped indiscriminately and are shoved towards the hopper 2 (Fig. 3) of the vertical tube 3 in which the coins form automatically a pile. The lower end of the vertical coin tube 3 is recessed or cut away throughout substantially half of its circumference to form a delivery slot or discharge opening 18 for the coins. The lowermost coin rests upon the guide member 4 upon which the slide 6 is movable between lateral guide ledges 5. The slide is forked at its front end and the end portions 7 of the tines of the fork are beveled or sloped inwardly to enable the fork to conform in some degree to the peripheries of the coins, so that the coin which the fork has seized is automatically centered. The slide 6 is accurately as

thick as a 1-pfennig-piece. At its rear end the slide is pivotally connected at 8 to a link 9 which is moved to and fro by a rocking arm 10 carried by a rotary shaft 11 supported in the frame of the device. The rocking arm is connected with a coupling sleeve 12 (see Fig. 2) journaled on a rod 11 mounted at its ends in the side frames of the machine. A similar coupling sleeve 13 likewise journaled on the rod 11, is releasably coupled with the sleeve 12 and firmly connected with a crank-arm 13' connected by a connecting rod 14 with a crank arm 14' driven by a pinion 15 meshing with a drive gear 16 manually rotatable by a crank 17.

At the side of the coin tube 3 and above the coin delivering slot 18 thereof is a cross rod 19 firmly supported in the frame of the device, on which cross rod is journaled a sleeve 20 to which a steel spring driving arm 21 is affixed. The lower end of this resilient arm is situated in front of the delivery slot 18 just in the middle of the path on which the coins are projected by the ejecting slide 5. Attached to the sleeve 20 is, furthermore, an upwardly extending arm 22, the upper end of which is connected with the operating lever 24 of the grand total counting mechanism 25 by the helical spring 23. The sleeve 20 is also provided with a depending arm 26, to the lower end of which is hinged a pawl-actuating member 27 having a lifting step or cam 28 and being slidably supported upon a forked member 29 projecting through and guided vertically by the walls of an aperture formed through the bottom or guide plate 4 of the device. The forked supporting member 29 is supported on one end of a rocker 30 pivoted at 30' to a hanger 30" depending from the guide plate 4. The weight of the counter-actuating member 27 resting on the supporting member 29 of the rocker 30 tends to rock the rocker counterclockwise (Fig. 1), but the supporting member 29 is held in raised or elevated position by a cam 31 fast on a cam shaft 31' extending between the side frames of the machine, the unmutilated periphery of the cam normally lying in contact with the remaining arm of the rocker 30. A handle 31" is fast on one end of the cam shaft 31'. The left-hand end of the pawl actuating member 27 with the lifting step or cam 28 can be lowered by turning the handle 31" to rotate the cam shaft 31' and its cam 31 sufficiently to position the mutilated or low portion of the cam opposite the forward arm of the rocker 30, whereupon the rocker turns counter-clockwise by gravity, lowering the forked support 29 and the pawl actuating member 27, which is thus displaced relatively to the counting mechanism for rouleaus or separate amounts of coins.

This counting mechanism includes the following elements.

A stationary dial 33 is applied to the exposed face of one of the side frames 100 of the machine, the face of the dial being conveniently graduated to a scale "0-100," there being provided a "free" or compensating space between the "0" and the "100" graduations, for a purpose hereinafter explained.

An adjusting shaft 32 journaled in the side frames of the machine projects at one end centrally of the dial 33 (see Fig. 1), the projecting end of the shaft having fixed thereon a pointer or hand 35 co-acting with the graduations on the dial. An adjusting knob 34 fast on the outer projecting end of the adjusting shaft enables the operator to turn the shaft and pointer to

position the pointer in line with any desired graduation.

A ratchet wheel 36 is fast on the adjusting shaft at a convenient point within the frame of the machine to turn with the shaft, the number of teeth on the ratchet wheel corresponding with the number of graduations of the dial.

Also a circular clutch-controlling disk 37 is secured to the adjusting shaft 32 within the machine, the periphery of the clutch-controlling disk 37 having an abruptly shouldered cam recess 38 formed therein, to normally accommodate the laterally turned follower 45 of a clutch-disconnecting member 46, in the form of an angular lever or bell crank pivoted at 47 within the machine frame.

In the normal position of the machine, the pointer 35 on the adjusting shaft 32 projects vertically upwardly to register with the numeral "100" on the dial, at which time the recess 38 of the clutch-controlling disk 37 is diametrically opposite below, in vertical alinement with the pointer 35, to accommodate the follower 45 on the clutch-disconnecting lever 46, said follower, when the machine is at rest, lying against the abrupt shoulder of the recess, to prevent the operator from turning the shaft, with its clutch-controlling disk, ratchet wheel 36 and pointer 35 in clockwise direction.

The vertical arm of the clutch-disconnecting bell crank 46 extends upwardly to a point adjacent a radially extending clutch-disconnecting stud 49 mounted on the rocking driving clutch sleeve 13 (see Fig. 1), which driving clutch sleeve is axially slidable along the rod 11 into and out of engagement with its co-acting drive clutch sleeve 12 likewise journaled on the rod 11. A spring 50 encircling the rod 11 between the left side frame 100 of the machine and the axially shiftable driving clutch sleeve 13 tends to hold the driving clutch sleeve or member releasably engaged with the driven clutch sleeve 12 connected with the coin-actuating slide 6.

However, the upper end or head of the vertical arm of the clutch-disconnecting bell crank 46 has formed thereon a cam face 48, and when the follower 45 lies in the cam recess 38, the spring 51 connected to the vertical arm of the bell crank, rocks the bell crank counterclockwise (Fig. 1) to enable the cammed face 48 of the vertical arm to co-act with the clutch disengaging stud 49 on the driving clutch member 13 and effect a disconnection of the clutch members.

To condition the machine for operation, the operator merely has to turn the knob 34 on the outer end of the shaft 32 to turn the pointer 35 and the clutch-controlling disk 37 connected therewith through a sufficient arc counterclockwise, to position the pointer in registry with the "0" graduation mark on the dial 33. The ratchet gear 36 also turns with the knob and the clutch controlling disk, but this is of no consequence.

The clutch-controlling disk, as it is thus rotated by the operator, causes the inclined edge of its abruptly shouldered cam recess 38 to cam the follower 45 radially outward, which rocks the clutch disconnecting bell crank 46 clockwise against the tension of its spring 51, to withdraw the cam face 48 on the vertical arm of the bell crank from the clutch disconnecting stud 49 on the driven clutch member 13, whereupon the clutch engaging spring 50 shifts the driving clutch sleeve 13 into coupling engagement with the driven clutch member 12, which latter member, through the

linkage 10, 9, is connected with the coin ejecting slide 6.

The "free" space between the "0" and "100" graduation marks permits this conditioning adjustment without interfering with the proper and accurate count of the coins, the angular distance of the arc defined by such "free" space corresponding to and compensating for the angular distance traversed by the shouldered recess 38 in camming the follower 45 out of the recess and onto the unmutilated periphery of the clutch-controlling disk 37.

To adjust the machine to repeatedly count fixed numbers of coins of like value for packaging in rouleaus, for example, or for other purposes, the operator turns the pointer 35 in counter-clockwise direction to that graduation on the dial 33, the difference between which graduation and "100" equals the number of like coins to be packaged. For example, if it is desired to obtain successive quantities of twenty coins, the operator will set the pointer to the "80" graduation, the difference between "80" and "100" being "20."

It will be recalled that as each coin is ejected from the coin tube 3 by the coin ejecting slide 6, such ejected coin collides with the lower free end of the depending arm 21 to rock said arm and the shaft 19 to which it is attached, counter-clockwise (Fig. 1), and that the shaft 19 is connected by a second arm 26 with one end of the actuating member 27, to reciprocate said member which is provided with a cam face 28.

This counter-clockwise rotation of the shaft 19 tensions a return spring 22' (Fig. 2) encircling the shaft 19, one end of the spring being conveniently anchored to the adjacent side wall 100 of the machine, the opposite end of the spring being secured to the arm 22.

The purpose of this spring is to restore the pawl actuating member 27 and the grand total counter arm 22 to their normal positions.

This reciprocating actuating member effects the count of the series of like quantities of coins as follows:

A quadrant-like bell crank 40 is journaled at its vertex on the adjusting shaft 32, the substantially horizontal arm of the bell crank 42 extending over the adjacent end of the reciprocating actuating member 27 and having a pawl 39 of resilient material mounted at its free end, the pawl extending upwardly adjacent the ratchet wheel 36. The free toothed end of the pawl 39 is off-set to engage the teeth of the ratchet wheel.

In its idle position, the horizontal arm of the quadrant-like bell crank 40, which arm carries a follower roll 41, lies at its normal limit of clockwise travel with its roll 41 resting on the low point of the cam 28 of its reciprocating actuating member 27.

Forward reciprocation of the pawl actuating member and its cam face 28 causes the latter to rock the quadrant-like bell crank 40 counter-clockwise (Fig. 1). The pawl 39 of the bell crank engaged with the ratchet 36, is thus caused to turn the ratchet, the clutch-control disk 37, shaft 32, knob 34 and pointer 35 in counter-clockwise direction relatively to the dial 33.

To restrict the movement of the ratchet wheel 36 and its connected parts to one step of travel and prevent overthrow, the free end of the upwardly extending arm of the quadrant-like bell crank 40 carries a laterally extending stop-lug 43 normally spaced apart from a pinion 42 by a distance approximately equal to the extent of 75

throw imparted to the bell crank and its pawl 39 by the reciprocating cam face 28 of the pawl actuating member 27. The pinion 42 is suitably journaled on a partition plate 101 (Fig. 2) and constantly meshes with the teeth of the ratchet wheel 36. As the bell crank 40 is completing its counter-clockwise stroke (Fig. 1), its laterally extending stop lug 43 enters between two of the teeth of the pinion 42 and is arrested by contact with the body of the pinion, thus terminating the extent of travel of the feed pawl 39 and determining the length of step imparted to the ratchet 36. The pinion 42 is also arrested and, because of its meshing engagement with the ratchet wheel, locks the ratchet wheel and its connected parts against overthrow due to momentum or inertia.

The coin-ejecting slide 6, in thrusting the ejected coin against the resilient arm 21, to rock the shaft 19, tensions the spring 22' and after the escape of the coin from beneath the arm 21, the spring 22' restores the arm 22, shaft 19, arms 21 and 26 and pawl-actuating member 27 to their normal positions, so that the roll 41 of the quadrantal pawl carrier 40 can again seat on the low point of the cam 28.

A spring-pressed ratchet detent 44 pivotally supported on the partition 101, engages the ratchet wheel 36 to permit counter-clockwise rotation thereof and prevent clockwise rotation. A spring 44a connected to the vertical arm of the quadrantal pawl carrier 40 is anchored to the pivot pin of the ratchet detent, such spring being tensioned as the pawl carrier and feed pawl 39 rock counter-clockwise. As soon, therefore, as the incline of the cam face 28 on the pawl actuating member 27 is again presented to the follower roll 41 of the quadrantal pawl carrier during the restoration of the actuating member to its idle position, the spring 44a rocks the pawl carrier 40 clockwise seating the follower roll 41 on the low point of the cam and withdrawing the feed pawl 39 idly over the teeth of the ratchet to position to take a new bite on the ratchet wheel. Incidentally, the stop lug 43 is withdrawn from between the teeth of the pinion 42, thus freeing the ratchet and pinion for rotation on the next stroke of the feed pawl.

As explained, the operator, in rotating the crank 17 effects an oscillation of the driving clutch sleeve or member 13 through the gears 15, 16, and the linked crank arms 14', 13'. This motion is communicated by the driving clutch sleeve 13 to the driven sleeve or co-acting clutch member 12 to reciprocate the coin ejecting slide 6, during which the spring 50 will yieldingly maintain the clutch member 13 engaged with the driven clutch member 12.

The operator will continue to turn the crank 60 17, and the foregoing operations will be repeated, the pointer 35 indicating such repeated operations successively by its step by step movement in counter-clockwise direction (Fig. 1) from the graduation "80" to the graduation "100." As the pointer arrives at the "100" graduation, the deepest portion of the cam recess 38 of the arresting disk 37 which has advanced with the pointer, is presented to the follower 45 of the clutch disconnecting lever, whereupon the spring 51 of the clutch-disconnecting angular lever 46 rocks said lever abruptly counter-clockwise to position the cam face 48 of the clutch-disconnecting angular lever 46 in effective relation with the stud 49 of the axially shiftable driving clutch member 13, whereupon the stud wipes along the cam face

48 which crowds the stud and its driving coupling member to the right (Fig. 2) axially of the rod 11, against the tension of the coupling spring 50 to disengage the driving clutch member from the driven clutch member 12 as the driving clutch member completes its oscillatory movement, and thus disconnects the power from the coin-ejecting slide 6.

Continued operation of the crank 17 will merely rock the driving clutch member 13 idly on its supporting rod 11, and the clutch-disconnecting stud 49 projecting from the clutch sleeve 13 will wipe back and forth on the cam face 48.

From the foregoing it is evident that in the idle position of the parts, the driving mechanism 15 can transmit no motion to the driven clutch 12 and hence the coin ejecting slide 6 remains stationary.

This manner of effecting the disengagement presents the advantage that the disengagement 20 of the drive takes place free of shocks in that the manually operable crank 17 can be further turned without harmful effect. The bell-crank lever 46 is, on the one hand, continually drawn by the helical spring 51 into the position in which the uncoupling of the drive is effected, it is true, but 25 on the other hand, it is likewise continually prevented from exerting that effect by the stop 45 bearing upon the rim of the disk 37 which is unmutilated on all other portions of its circumference, the end-position "100", constituting, 30 however, an exception as regards the action of the pinion 42 upon the angularly bent end 43 at the other arm of the bell-crank lever 40.

It will also be clear from the foregoing description, that the cam slide or member 27 will remain in operative relation with the counter actuator or bell crank 40 as long as the unmutilated periphery of the cam 31 (Fig. 1) remains engaged with the free end of the rocker 30. When it is desired to suspend the count of coins 35 by equal lots, the cam shaft 31' is rotated to locate the low point or dwell of the cam over the free end of the rocker. This enables the weight of the cam slide 27 to tilt the rocker counter-clockwise to lower its forked slide-support 29, and the slide rocks downwardly with the support. The counter actuator 40 also swings downwardly 40 in clock-wise direction during the initial movement of the slide until the off-set lug 43 at the upper end of the vertical arm of the counter-actuator 40 contacts the detent 44, or a suitable 45 stop pin (not shown), which arrests farther clockwise follow-up movement of the bell crank and pawl. The cam slide 27, however, continues its counter-clockwise travel until the high dwell of its cam 28 lies a sufficient distance beneath the roll 41 of the bell crank or counter actuator so that the cam slide cannot actuate the bell 50 crank.

To facilitate the adjustment of the pointer or hand 35 and the conditioning of the repeat counter to count various like numbers of coins to be packaged, as a succession of ten, twenty, thirty, etc., coins to the package, and also to obviate errors in the adjustment, intermediate stop members 52 (Fig. 2), are provided which can be projected beyond the plane of the dial so as to block the path of the hand or pointer. These intermediate stops 52 are normally retained by springs 53 so that their outer ends are retracted 55 within the plane of the stationary graduated disk 33, but they can be manually projected outwardly temporarily by depression of their respective keys, each key having its individual lever 54 75

suitably pivoted on the inner face of the side frame 100, the free inner end of each lever lying beneath its appropriate intermediate stop 52. The selected stop projecting key 55 is held depressed to retain the corresponding intermediate stop in effective position until the hand or pointer has been adjusted to contact therewith, after which the selected key 55 may be released whereupon the projected intermediate stop is retracted by its spring 53 to its normal idle position.

Fig. 3 shows a transverse section through the coin table 1. The left-hand portion of this table is situated above the counting mechanism, whereas the right-hand portion of said table can be turned downwardly around the hinge 56 to the position indicated by dot-and-dash lines to which the reference numeral 1 is also applied. Simultaneously therewith that part of the swinging end portion of the table which extends to the left (Fig. 3) of the hinge is upwardly turned so that a rim 57 is formed which completes the enclosure wherein the coins are initially dumped. This arrangement renders, therefore, possible not only a reduction of the space requisite for the device during transport, but also while the device is used for smaller amounts of coins, as in this case the remaining smaller portion of the table can be fully utilized owing to the existence of the above mentioned complete rim. The bracket 58 provided for supporting the swinging portion of the table in its horizontal position, is laterally turnable.

The coins ejected one by one by the slide 6 slide down the inclined chute or way 59 after they have actuated the spring arm 21 in the manner above described. Resilient supporting members 61 are conveniently fastened at their upper ends at 60 to the opposed inner faces of the side walls of the chute 59, which resilient supports extend beyond the lower open end of the chute, headed studs 62, 63 being mounted in such protruding ends.

The free ends of the resilient supports can be pressed towards each other against their tension to enable the suspension of a coin collecting tube 65 therefrom, the upper end of the tube being provided with bayonet slots 64, as shown in Fig. 4. The range of elasticity of the resilient supports 61 is sufficient to permit the selective suspension of collecting tubes for coins of various diameters. As the resilient supports form at the same time laterally adjustable walls due to the flexing of the supports to fit them to the coin tubes, and hence the coins, of various diameters, an automatically centered feed of the coins to the small, as well as to the large collecting tubes is obtained whereby an accurate introduction of the coins into said tubes is effected.

It will be understood that because of the particular method of setting the hand 35 (Fig. 1) 60 and clutch control disk 37, the clutch disengaging feature is retained irrespective of the adjustment of the counter for various numbers or quantities of coins to the rouleau. Thus, whether the counter is set to count the coins in repeated batches or lots of 20, 40, 50 or 100 units, the ejection of the last coin making up the selected lot 65 will result in the disengagement of the clutch sleeves 12 and 13 with a consequent cessation of the ejection of the coins and the counting thereof, until the clutch control disk is reset.

I claim:

1. A coin counting device comprising a coin stack container; a coin ejector to eject the coins one by one from the container; means to drive the coin ejector; an arm operable by the coins

as they are successively ejected; a counting ratchet; a cam member connected to said arm for operation thereby; a rocking pawl actuated by said cam member, and intermittently engaging said ratchet to advance the latter step by step; a notched disk connected with said counting ratchet; a coupling mechanism between the drive means and the coin ejector; and a coupling control member engageable with the periphery of the notched disk, the unmutilated periphery of which disk maintains the coupling control member ineffective, and the notched portion of which disk releases the coupling control member to effect disconnection of the coupling mechanism.

2. A counting device including a container for stacked coins; a coin ejector to eject the coins one by one from the container; means to drive the coin ejector; a rocking spring-pressed arm extending into the path along which said coins are ejected, to be rocked in one direction by said coins as they are successively ejected; a reciprocable cam member connected with, and operable by said rocking arm; a movable supporting member for the cam member; a counting mechanism; means with which the cam member co-acts and operable from and towards a normal home position, to actuate the counting mechanism step by step; and means to adjust said movable supporting member to position said cam member into and out of operative relation with said actuating means for the counting mechanism to enable or disable said counting mechanism at will.

3. A coin counting device including a container for the stacked coins; a coin ejector to eject the coins one by one from the container; an arm extending into the path of, and operable by each coin as it is ejected; a drive for the coin ejector; connectible and disconnectible clutch means interposed between the drive and the coin ejector; a counting mechanism; a rotatable clutch control disk connected with the counting mechanism; means operable by said arm to advance the counting mechanism and its disk step by step from a predetermined constant starting point clutch disconnecting means; and means controlled by said clutch control disk and effective, when the disk has advanced to a predetermined point, to enable the clutch disconnecting means to disconnect the clutch means.

4. In a coin-counting machine, the combina- 50

tion with a coin stacker; a drive mechanism; coin ejecting means operable by the drive mechanism to eject the coins one by one from the bottom of the coin stacker; a step by step repeat counter to count numbers of coins; means to variously adjust the counter to count the coins in lots of various numbers as desired; means operable by the coins as they are respectively ejected, to advance the repeat counter step by step; and a releasable clutch between the drive and the coin-ejecting means; of a clutch control disk shiftable step by step with the counter; means to arrest the clutch control disk against rotation in one direction, at a predetermined point in the rotation of the disk; and means associated with the arresting means for the clutch control disk, to disengage the clutch synchronously with the ejection of the last coin completing the number for which the counter has been set.

5. In a coin counting machine, the combination with a coin container; a drive mechanism; coin-ejecting means operable by the drive mechanism to eject the coins one by one from the coin container; a step by step repeat counter to count the numbers of coins ejected in lots; and means operable by the coins as they are ejected to advance the repeat counter step by step; of a releasable clutch including interengaging clutch members interposed between the drive mechanism and the coin ejecting means, one of said clutch members being shiftable towards and from its co-acting clutch member; a clutch control disk connected with the counter for rotation therewith; a clutch control member having an arm with which the clutch control disk coacts to control the position of the control member; a second arm on said clutch control member to co-act with said shiftable clutch member, said clutch control disk being returnable by the means for advancing the counter from any of its set positions to render the clutch control member effective at a predetermined constant position of said clutch control disk and counter to automatically disconnect the clutch members, said clutch control disk, when set to starting position, being effective to shift the clutch control member to idle position; and means to re-engage the clutch members upon the withdrawal of the clutch control member to its idle position.

EUGEN REIS.
